UNITED STATES PATENT OFFICE.

SWAN SMITH AND OSCAR W. HAMMERQUIST, OF RAMSEY COUNTY, MINNESOTA.
ASSIGNORS, BY DIRECT AND MESNE ASSIGNMENTS, TO OSTERLIND PRINTING
PRESS AND MANUFACTURING COMPANY, OF ST. PAUL, MINNESOTA, A CORPO-
RATION OF MINNESOTA.

PRINTING-PRESS.

1,167,665.

Specification of Letters Patent. Patented Jan. 11, 1916.

Application filed April 22, 1912. Serial No. 692,421.

To all whom it may concern:

Be it known that we, SWAN SMITH and OSCAR W. HAMMERQUIST, citizens of the United States, residing in Ramsey county, in the 5 State of Minnesota, have invented new and useful Improvements in Printing-Presses, of which the following is a specification.

Our invention relates to printing presses of the cylinder type.

10 Its object is to provide a simple, durable and efficient press having a reciprocating impression cylinder and a movable bed adapted to co-act with the impression cylinder.

15 A further object is to provide in a printing press of this class means for manually dropping the bed and discontinuing the operation of the inking mechanism irrespective of the movement or position of the impression cylinder.

20 A further object is to provide means for insuring a perfect register between the impression cylinder and the bed.

In the drawings Figure 1 is a side elevation of our improved press; Fig. 2 is an end elevation of the same with the feeding platform removed; Fig. 3 is a sectional view taken on the line 3—3 of Fig. 2 and Fig. 4 is a detail sectional view showing the cylinder and bed with its operating mechanism.

25 Referring to the drawings, we have used the reference numeral 10 to indicate the press frame, 11 the impression cylinder, 12 the bed, 13 the feeding platform and 14 the 30 delivery platform.

The impression cylinder 11 is rotated continuously and is adapted to move backward and forward above the bed 12 from the feeding platform 13, where it rests to receive a 35 sheet of paper to the delivery platform 14, where it again rests to discharge the printed sheet. The carriage members 15 are movable on the slides 16 of the frame 10 and form bearings in which the ends of the cylinder supporting shaft 11^a are journaled. The 40 cam shaft 17 in the frame 10 is provided with a double faced cam 18 and is operatively connected through the gear wheels 19 and 20 with the power pulley 21. A segment 22, provided at each end with a cam roller 23, is fixed to the rock shaft 24 on the frame 10. Each face of the double cam

18 engages a roller 23 and when rotated rocks the shaft 24 backward and forward. A pair of upwardly extended levers 25 are 55 fixed at one end to the rock shaft 24, each lever being pivotally attached at its upper end to a connecting rod 26 which is also pivotally attached to one of the carriage members 15. The faces of the cam 18 are 60 angularly spaced apart, each comprising a neutral low portion, an active outwardly extending part, a neutral high portion and an inwardly extending part. The active portions cause opposite strokes of the cylinder 11 and the neutral portions retain said cylinder for a predetermined interval at the end of each stroke.

The cam shaft 17, counter shaft 27 and shaft 28 are respectively provided with 70 meshing spur gears 29, 30, and 31 and the shaft 33, journaled in the frame 10, is driven by the shaft 28 through the beveled gear wheels 34 and 35 located respectively on the shafts 28 and 33. The cylinder supporting 75 shaft 11^a is driven continuously from said shaft 33 by means of the spiral gears 36 and 37. The gear 36 is fixed on the shaft 11^a and its meshing gear 37 is feathered on the shaft 33. Said gear 37 is retained in mesh 80 with its companion gear 36 and is shifted on the shaft 33 by the arms 38 of the bracket 39 on the carriage member 15 adjacent to said shaft 33.

To insure perfect registry between the impression cylinder 11 and the type form in the bed 12, we have fitted the cylinder 11 with a gear 40 and the bed 12 with a rack 41 adapted to mesh with said gear when the cylinder 11 is in contact with the form.

The bed 12 slidable on its posts 12^a of the frame 10 is normally elevated when the cylinder 11 moves forward, thus causing said cylinder to bear against the form contained in said bed and is lowered to prevent contact 95 between said form and cylinder as the latter moves back. Slidable journal boxes or bearings 42 beneath the bed 12 receive the eccentric shafts 43 which are journaled at their ends in frame 10. Each of these shafts 100 is provided with an arm 44, said arms being connected by a link 45 to synchronize the movement between said shafts. The lever 46 is loosely mounted at one end on

one of the shafts 43 and is provided with a curved slot 47 to receive the bolt 48 by means of which said lever is adjustably secured to one of the arms 44. The free end of the lever 46 is connected by the link 46^a to the free end of the cam lever 49, which is pivotally mounted at its other end on the frame 10. This lever is provided with a cam roller 50 arranged in engagement with the inside 10 cam 51 on the counter shaft 27, and is intermittently oscillated by said cam. Said lever 49 operates through the link 46^a, lever 46 and arms 44 to rock the eccentric shafts 43, thus elevating the bed 12 on the forward 15 stroke of the cylinder and lowering it on the return stroke of said cylinder.

The shaft 28 is provided with an inking roller 52. This roller is supplied with ink from the ductor roller 53, which gathers its 20 supply from the fountain roller 54. Ink distributing rollers 55 on the frame 10 are provided for said roller 52. The form rollers 56 on the carriage members 15 contact with the roller 52 at the end of their forward 25 stroke to receive a supply of ink therefrom. We arrange and operate the ductor and fountain rollers as follows: The ductor roller 53 is mounted in a pair of arms 57 extending from the shaft 58 journaled in the 30 frame 10. The lever 59 on this shaft is pivotally connected through the yoke 60 with the eccentric stud 61 on the beveled gear wheel 34 and is operated thereby to swing the ductor roller 53 from the adjacent fountain roller 54 in the ink fountain 62 to the inking roller 52. The spring 63 between the 35 frame 10 and one of the arms 57 operates to return said roller to a position in contact with the fountain roller 54. The loosely 40 mounted lever 64 on the fountain roller shaft 65 is provided with a pawl 66 in engagement with the ratchet 67 on said shaft and is connected by the link 68 with one of the arms 57. The movement of this arm 57 is communicated 45 through said link, lever and ratchet to rotate the fountain roller 54 and supply the same with ink.

During the operation of a printing press it is often desirable to prevent contact 50 between the form and impression cylinder during one or more strokes of the latter, and it is then of course desirable to discontinue the action of the inking mechanism. We have provided the following mechanism 55 whereby the bed may be instantly lowered and the inking operation automatically discontinued. The free end of the lever 46 on one of the shafts 43 is provided with the slideway 69 terminating at one end in the 60 socket 70. The connection between the link 46^a and this lever consists of a pin 71 in said link adapted to rest in said socket 70. In the normal operation of the press this 65 pin is retained in said socket and the cam lever 49 rocks the eccentric shafts 43 through

the link 46^a, lever 46 and arms 44 as above described. We have supplied the guide bar 72 with a pivotal and slidable mounting at one end on the frame 10 and have arranged the bell crank 73 in operative connection 70 with said bar and the foot lever 74 on said frame. A slight movement of this lever 74 raises the guide bar which removes the pin 71 from the socket 70. The displacement of this pin changes the pivotal connection between the lever 46 and the link 46^a to a 75 slidable one and permits the spring 75 between the bed 12 and link 45 to act and move the arms 44 to position lowering the bed regardless of the position or operation of the 80 cam lever 49. In shifting this guide bar 72 to position releasing the pin 71 from its 85 socket 70, said bar is also moved forward and extended into the path of the arm 76 on the shaft 58 to prevent the rotation of said 90 shaft and the engagement of the ductor roller 53 with the fountain roller 54. As above described, the ductor roller is thus 95 swung from the fountain roller 54 to the inking roller 52 by the connecting mechanism between the shaft 28 and the beveled gear wheel 34, and is then returned by the 100 spring 63. The guide bar 72 prevents the movement of the shaft 58 when turned, by the action of said spring. We have provided the arm 76 with a spring dog 77 movable in one direction. This resilient dog is intended to prevent damage to the guide bar 72 in case said bar should be extended 105 into the path of the arm 76, as the ductor 110 roller 53 passes from the fountain roller 54 to the inking roller 52. Means are also present for receiving sheets of paper from the cylinder 11 and moving the same to the delivery platform 14. The rock shaft 78 is 115 supported on the frame 10 and provided with a lever 79 which is supplied with a connecting rod 80 attached to the spur gear 31 on the shaft 28. Swinging arms 81 fixed on this shaft, carry rods 82 and 83 adjacent 120 to each other. The rod 82 is adjustably secured in said arms 81 while the second rod 83 is loosely mounted therein. The rods 82 and 83 are respectively provided with a plurality of co-acting jaws 84 and 85 and the 125 upper rod 83 is also provided with a spring actuated roller arm 86 adapted to yieldingly secure said rod in position and normally hold the pairs of jaws together. The arms 81 are oscillated backward and forward over 130 the delivery platform. At the end of their backward stroke the roller arm 86 engages the cam surface 87, and the jaws 85 are opened to receive a sheet of paper as the same is stripped from the cylinder by the fingers 88. On the return stroke of said arms 81 the roller arm 86 is disengaged from the cam surface 87 and the jaws 84 and 85 grip and carry the sheet forward over the delivery platform. Near the end of the re- 135

turn stroke the roller arm 86 engages the cam surface 89 to open the jaw members 85 and the stop fingers 90 engage and release the sheet from said jaws, said sheet being 5 then free to fall into its proper position on the delivery platform.

In operation, sheets of paper are successively fed to the impression cylinder 11, which is provided with ordinary grips 91 (diagrammatically illustrated in Fig. 2) and associated operating mechanism. This cylinder passes over the bed 12 and delivers the printed sheets to the delivery jaws 84 and 85. These jaws carry said sheets to their proper position over the delivery platform 14 and release the same in such position. The bed 12 is normally elevated on the forward stroke of the cylinder 11 to cause it to bear against the form and is lowered on the 20 return stroke of the cylinder to prevent such contact. The bed may be instantly lowered by operating the foot lever 74 and the inking operation is thereby discontinued.

What we claim as our invention and desire to protect by Letters Patent, is:

1. In a printing press, the combination of a frame, a bed on said frame, an impression cylinder for said bed, means for engaging said bed and cylinder on the forward stroke 30 of the latter, power driven means for constantly rotating said cylinder in one direction and power driven means for intermittently reciprocating the cylinder and for synchronizing its reciprocating movement 35 with respect to the rotation thereof whereby said cylinder is held at the ends of its strokes to permit the rotation of the same to positions for receiving and discharging sheets of paper and for registering said 40 cylinder and bed on the forward stroke of the former.

2. In a printing press, the combination of a frame, an impression cylinder on the frame, means for intermittently reciprocating and continuously rotating said cylinder, a movable bed on said frame, power operated means for normally elevating the bed during the forward stroke of the cylinder and for lowering said bed during the return 50 of said cylinder, and means for manually lowering and discontinuing the movement of said bed.

3. In a printing press, the combination of a frame, a bed on said frame, an impression cylinder for said bed, mechanism for intermittently engaging said bed and cylinder, means for continuously rotating said cylinder and separate means for reciprocating said cylinder in a straight path and for 60 holding the same at the beginning and end of the printing stroke, whereby during the pause in reciprocation at the beginning of a stroke a sheet may be fed to the cylinder, while rotating, and carried a substantial distance to printing position and during the 65

pause in reciprocation at the end of a stroke the sheet may be withdrawn from printing position and ejected from the press by said rotating cylinder.

4. In a printing press, the combination of a frame, a bed movable on said frame, an impression cylinder for said bed, means for continuously rotating said cylinder and for intermittently reciprocating the same on said frame and means for raising and lowering 75 said bed and for correlating the movement thereof with that of said cylinder.

5. In a printing press, the combination of a frame, a reciprocating impression cylinder on said frame, a bed on the frame, a form 80 in said bed, mechanism for inking the form, a ductor roller for supplying said mechanism with ink, power operated means for normally reciprocating said bed vertically and for timing its movement with respect 85 to that of said cylinder, resilient means tending to lower the bed and manually operated means for discontinuing the operation of the ductor roller and rendering said first mentioned means inoperative whereby 90 the action of said resilient means is permitted to instantly lower and prevent the movement of said bed.

6. In a printing press, the combination of a frame, carriage members slidable horizontally on said frame, an impression cylinder journaled in said carriage members, a power driven cam shaft on the frame, a cam on said shaft, a rock shaft on the frame, a segment on said shaft in operative connection with said cam, levers on said rock shaft, rods pivotally connecting said levers and carriage members and a vertically movable bed on said frame.

7. In a printing press, the combination of a frame, an impression cylinder revoluble in and slidably mounted on said frame, means for reciprocating said cylinder, eccentric shafts in the frame, a bed mounted on said shafts, a lever on each of said shafts, a connecting link between said levers, a spring between said bed and link adapted to move the levers, one of said levers having a slide therein terminating at one end in a socket, a power shaft on the frame, an inside cam on said power shaft, a cam lever pivoted at one end on the frame and in operative connection with said cam, a link pivotally connected at one end to the free end of said cam lever and at its other end provided with a pin, said pin being adapted to normally rest in said socket and form a connection between said link and said lever having the slide, whereby upon movement of said cam lever, the levers on said eccentric shafts are oscillated and the bed raised and lowered, a guide bar pivotally mounted at one end on the frame, a foot lever on said frame and a bell crank in operative connection with said foot lever and guide bar, said 105 110 115 120 125 130

guide bar being adapted to move said pin from said socket and retain the same in said slide.

8. In a printing press, the combination of 5 a frame, an impression cylinder revoluble in and slidably mounted on said frame, means for continuously revolving and reciprocating said cylinder, eccentric shafts journaled in the frame, connecting means between the 10 shafts, a bed mounted on said shafts, a lever on one of the shafts, a power shaft on the frame, an inside cam on said shaft, a cam lever pivoted at one end on the frame and in operative connection with said cam, and 15 a link pivotally connected at one end to the free end of said cam lever and at its other end to said first mentioned lever.

9. In a printing press, the combination of 20 a frame, an impression cylinder revoluble in and slidably mounted on said frame, means for reciprocating said cylinder, eccentric shafts in the frame, a bed mounted on said shafts, a lever on one of said shafts having a slide therein and terminating at one end in 25 a socket, a power shaft on the frame, an inside cam on said power shaft, a cam lever pivoted at one end on the frame and in operative connection with said cam, a link pivotally connected at one end to the free end 30 of said cam lever and at its other end provided with a pin, said pin being adapted to normally rest in said socket and form a connection between said link and lever whereby upon movement of said cam lever the first 35 mentioned lever is oscillated and the bed raised and lowered, a guide bar pivotally mounted at one end on the frame, a foot lever on said frame and a bell crank in operative connection with said foot lever and 40 guide bar, said guide bar being adapted to move said pin from said socket and retain the same in said slide.

10. In a printing press, the combination of 45 a frame, an impression cylinder revoluble in and slidably mounted on said frame, means for continuously revolving and for reciprocating said cylinder, eccentric shafts journaled in the frame, a vertically movable bed mounted on said shafts, an arm on each 50 shaft, a connecting link pivotally attached to the ends of said arms to synchronize the movement of said shafts, a lever on one of the shafts and means for oscillating the same to turn said shafts and thereby raise 55 and lower said bed.

11. In a printing press, the combination of 60 a frame, an impression cylinder revoluble in and slidably mounted on said frame, a power shaft, means in operative connection with said shaft for reciprocating said cylinder, gearing connecting said shaft and cylinder for continuously rotating the latter, eccentric shafts journaled in the frame, a bed mounted on said shafts, an arm on each 65 of said shafts, a connecting link pivotally

attached to the ends of said arms, a lever loosely mounted at one end on one of said shafts and having a curved slot therein, a bolt in one of said arms for fixing and adjusting said lever with respect to said arm, 70 and means for oscillating the said lever to raise and lower the bed.

12. In a printing press, the combination of 75 a frame, an impression cylinder revoluble in and slidably mounted on said frame, means for reciprocating said cylinder, eccentric shafts journaled in the frame, a bed, vertical guides for said bed, bearings on said shafts slidably horizontally beneath said bed, and forming a mounting therefor, 80 an arm on each of said shafts, a connecting link pivotally attached to the ends of said arms, a lever on one of the shafts, and means for oscillating the same to turn said shafts and thereby raise and lower said bed.

13. In a printing press, the combination 85 of a frame, an impression cylinder revoluble in and slidably mounted on said frame, means for reciprocating said cylinder, eccentric shafts journaled in the frame, a bed 90 mounted on said shafts, vertical guides for said bed, an arm on each of said shafts, a connecting link pivotally attached to the ends of said arms, a lever on one of the shafts, and means for oscillating the same 95 to turn said shafts and thereby raise and lower said bed.

14. In a printing press, the combination 100 of a frame, an impression cylinder revoluble in and slidably mounted on said frame, means for reciprocating said cylinder, eccentric shafts in the frame, bearings on said shafts, a bed mounted on said bearings, a lever on one of said shafts having a slide 105 therein and terminating at one end in a socket, a power shaft on the frame, an inside cam on said shaft, a cam lever pivoted at one end on the frame and in operative connection with said cam, a link pivotally connected at one end to the free end of said 110 cam lever and at its other end provided with a pin, said pin being adapted to normally rest in said socket and form a connection between said link and lever whereby upon movement of said cam lever, the first mentioned lever is oscillated and the bed raised and lowered, a guide bar pivotally mounted at one end on the frame, a foot lever on said frame, and a bell crank in operative connection with said foot lever and guide bar, 115 said guide bar being adapted to move said pin from said socket and retain the same in said slide.

15. In a printing press, the combination 120 of a frame, an impression cylinder revoluble in and slidably mounted on said frame, means for reciprocating said cylinder, eccentric shafts in the frame, an arm on each of 125 said shafts, a connecting link between said arms, to synchronize the movement of said 130

- shafts, a bed mounted on said shafts, a lever on one of said shafts having a slide therein and terminating at one end in a socket, a power shaft on the frame, an inside cam on 5 said shaft, a cam lever pivoted at one end on the frame and in operative connection with said cam, a link pivotally connected at one end to the free end of said cam lever and at its other end provided with a pin, 10 said pin being adapted to normally rest in said socket and form a connection between said link and lever whereby upon movement of said cam lever the first mentioned lever is oscillated and the bed raised and lowered, 15 a guide bar pivotally mounted at one end on the frame, a foot lever on said frame, and a bell crank in operative connection with said foot lever and guide bar, said guide bar being adapted to move said pin from said socket and retain the same in said slide. 20
16. In a printing press, the combination of a frame, an impression cylinder revolvable in and slidably mounted on said frame, means for reciprocating said cylinder, eccentric shafts in the frame, an arm on each of said shafts, a connecting link between said arms, a bed mounted on said shafts, a lever on one of said shafts having a slide therein and terminating at one end in a socket, 25 means for adjustably connecting said lever with one of said arms, a power shaft on the frame, an inside cam on said shaft, a cam lever pivoted at one end on the frame and in operative connection with said cam, a link pivotally connected at one end to the free 30 end of said cam lever and at its other end provided with a pin, said pin being adapted to normally rest in said socket and form a connection between said link and lever 35 whereby upon movement of said cam lever, the first mentioned lever is oscillated and the bed raised and lowered, a guide bar pivotally mounted at one end on the frame, a foot lever on said frame, and a bell crank in 40 operative connection with said foot lever and guide bar, said guide bar being adapted to move said pin from said socket and retain the same in said slide. 45
17. In a printing press, the combination of a frame, an impression cylinder revolvable in and slidably mounted on said frame, means for reciprocating said cylinder, a pair of eccentric shafts in the frame, arms on 50 said shafts, a connecting link between said arms, a bed mounted on said shafts, a lever on one of said shafts having a slide therein and terminating at one end in a socket, a power shaft on the frame, an inside cam on 55 said shaft, a cam lever pivoted at one end on the frame and in operative connection with said cam, a link pivotally connected at one end to the free 60 end of said cam lever and at its other end provided with a pin, said pin being adapted to normally rest in said socket and form a connection between 65 said socket and form a connection between
- said link and lever whereby upon movement of said cam lever the first mentioned lever is oscillated and the bed raised and lowered, a guide bar pivotally mounted at one end on the frame, a foot lever on said frame, a bell 70 crank in operative connection with said foot lever and guide bar, said guide bar being adapted to move said pin from said socket and retain the same in said slide and a spring between said connecting link and bed 75 for turning said eccentric shafts to lower the bed when said pin is removed from its socket. 80
18. In a printing press, the combination of a frame, an impression cylinder revolvable in and slidably mounted on said frame, means for reciprocating said cylinder, a pair of eccentric shafts in the frame, arms on said shafts, a connecting link between said arms, a bed mounted on said shafts, a lever 85 on one of said shafts having a slide therein and terminating at one end in a socket, a power shaft on the frame, an inside cam on said shaft, a cam lever pivoted at one end on the frame and in operative connection with 90 said cam, a link pivotally connected at one end to the free end of said cam lever and at its other end provided with a pin, said pin being adapted to normally rest in said socket and form a connection between said link and lever 95 whereby upon movement of said cam lever the first mentioned lever is oscillated and the bed raised and lowered, an inking roller on the frame, a shaft revolvable in the frame, a pair of supporting arms on said shaft, a ductor roller carried by said arms, means for swinging said roller back and forth between the inking and fountain rollers, an arm on said last mentioned shaft, a guide bar pivotally mounted at one end on the frame, a foot lever on said frame, a bell 100 crank in operative connection with said foot lever and guide bar, said guide bar being adapted to move said pin from said socket and obstruct the movement of said arm to 105 prevent contact between the ductor and fountain rollers. 110
19. In a printing press, the combination of a frame, an impression cylinder on said frame, a bed on the frame, means for continuously rotating said cylinder, a power driven cam in operative connection therewith for intermittently reciprocating said cylinder, said cam having two surfaces, each comprising an outwardly extending active 115 portion to move the cylinder in one direction, an inwardly extending portion to permit the return of the cylinder and neutral circular surfaces, joining said portions, for holding said cylinder against reciprocation 120 at the end of its stroke to permit the rotation of the same to a position for receiving and discharging sheets of paper. 125
20. In a printing press, the combination of the frame, a continuously revolvable and in- 130

- termittently reciprocating impression cylinder on said frame, a bed on the frame, means for normally elevating the bed during one stroke of the cylinder and for lowering said bed on the return stroke of said cylinder, an inking roller on the frame, distributing rollers for said inking roller, a fountain roller adjacent to the inking roller, a ductor roller movable between the inking and fountain rollers, means for manually lowering and discontinuing the movement of said bed and for concurrently preventing the engagement of the ductor roller with said fountain roller.
- 15 21. In a printing press, the combination of a frame, a continuously revoluble and intermittently reciprocating impression cylinder on said frame, a bed on the frame, means for normally elevating the bed during one stroke of the cylinder and for lowering said bed on the return stroke of said cylinder, a power driven shaft, an inking roller on said shaft, distributing rollers for said inking roller, a fountain roller adjacent to the inking roller, a second shaft revoluble on the frame, arms on said shaft, a ductor roller carried by said arms, means for swinging said roller from the inking roller to the fountain roller, and means for manually lowering and discontinuing the movement of said bed and for preventing the engagement of the ductor roller with said fountain roller.
- 25 22. In a printing press, the combination of a frame, an impression cylinder revoluble in and slidably mounted on said frame, means for reciprocating said cylinder, a bed on the frame, a power driven shaft arranged transversely to said cylinder, a spiral gear on the cylinder and a second spiral gear feathered on said shaft and secured in mesh with said first mentioned gear.
- 35 23. In a printing press, the combination of a frame, an impression cylinder revoluble in and slidably mounted on said frame, means for reciprocating said cylinder, a bed movable vertically on the frame, a power
- 40 driven shaft, a gear feathered on said shaft, and a gear on said cylinder in mesh with said last mentioned gear. 50
- 45 24. In a printing press, the combination of a frame, an impression cylinder on the frame, means for continuously rotating and intermittently reciprocating said cylinder, a gear on the cylinder, a bed on the frame, a rack on said bed, means for raising said bed and meshing said gear with said rack during one stroke of the cylinder, and for lowering the bed and preventing said rack from meshing with said gear during the return stroke 60 of said cylinder.
- 25 25. In a printing press, the combination of a frame, carriage members slidable on said frame, a shaft journaled in said members, a gear on said shaft, an impression cylinder mounted on the shaft, means for intermittently reciprocating said cylinder, a bed on the frame, a power shaft on the frame, a gear feathered on said power shaft and in mesh with said first mentioned gear. 65
- 26 26. In a printing press, the combination of a frame, carriage members slidable on said frame, a shaft journaled in said members, an impression cylinder mounted on said shaft, gear wheels on the shaft, means for reciprocating said cylinder, a bed movable vertically on the frame, a rack on said bed adapted to mesh with one of said gear wheels, a power shaft on the frame, a gear feathered on said shaft and adapted to mesh 80 with the other gear on said cylinder, and a bracket on one of said carriage members for shifting the feathered gear on said power shaft and for retaining the same in mesh with its companion gear. 85
- In testimony whereof, we have signed our names to this specification in the presence of two subscribing witnesses.
